UNITED STATES PATENT OFFICE.

ALPHONSO M. HYDE, OF WEST HAVEN, CONNECTICUT, ASSIGNOR TO THE WEST HAVEN BUCKLE COMPANY, OF SAME PLACE.

SNAP-HOOK.

SPECIFICATION forming part of Letters Patent No. 430,384, dated June 17, 1890.

Application filed September 23, 1889. Serial No. 324,752. (No model.)

To all whom it may concern:

Be it known that I, ALPHONSO M. HYDE, of West Haven, in the county of New Haven and State of Connecticut, have invented new improvements in Snap-Hooks; and I do hereby declare the following, when taken in connection with accompanying drawings and the letters of reference marked thereon, to be a full, clear, and exact description of the same, and which said drawings constitute part of this specification, and represent, in—

Figure 1, a perspective view of a snap-hook embodying my invention; Fig. 2, an enlarged view in central longitudinal section.

My invention relates to an improvement in snap-hooks particularly designed to be used in the manufacture of suspenders or braces, the object being to provide a simple, cheap, and effective hook for this purpose.

With these ends in view my invention consists in a snap-hook having its tongue and the actuating-spring thereof made in one piece of metal, and in certain details of construction, as will be more fully hereinafter described.

The body of the hook, as herein shown, is made in one piece of metal, and comprises the eye A, the shank B, having the upturned ears C C, and the hook D. The tongue E and its actuating-spring F are formed from a single piece of metal, the spring virtually forming an extension of the outer end of the tongue and resting and sliding upon the inner face of the shank B of the body. The tongue is provided about midway of its length with two

perforated ears G G, each bent down at an angle with it and receiving in their perforations fingers H H, bent inward and formed at the outer ends of the ears C C. The inner end of the tongue is engaged with the outer edge of the loop, whereby the tendency of the spring to throw the inner end of the tongue down is resisted. By making the tongue and the actuating-spring therefor in one piece of metal the number of separate parts in the complete hook is reduced and the making and assembling of the hook simplified.

I am aware that hooks of this class have been constructed with the tongue and spring formed from one piece of metal, and I do not therefore wish to be understood as claiming, broadly, such as my invention; but

What I do claim is—

In a snap-hook, the combination of the body B, terminating in a hook D at one end, with the tongue E, hung upon a pivot in the body midway of its length to open upward, one end of said tongue extending to and adapted to engage said hook, the other extending from the pivot to form a handle and at its extreme end returned toward the body and toward the pivot to form a spring F, the bearing of the spring upon the body being forward of the end of the handle and near the pivot, substantially as described.

ALPHONSO M. HYDE.
